DESIGN FOR A LUNCH BOX OR SIMILAR ARTICLE

Everett Worthington, Scarsdale, N. Y., assignor to American Can Company, New York, N. Y., a corporation of New Jersey

Application July 14, 1938, Serial No. 78,483

Term of patent 14 years

To all whom it may concern:

Be it known that I, Everett Worthington, a citizen of the United States, residing at 15 Oak Lane, village of Scarsdale, county of Westchester and State of New York, have invented a new, original, and ornamental Design for a Lunch Box or Similar Article, of which the following is a specification, reference being had to the accompanying drawing, forming a part thereof.

Fig. 1 is a perspective view of a lunch box or similar article showing my new design and

more particularly showing the front side of the box with the carrying handle in partially raised position to show details of design.

Fig. 2 is a perspective view of the same box showing the rear side of the box with the carrying handle in lowered position.

I claim:

The ornamental design for a lunch box or similar article, as shown and described.

EVERETT WORTHINGTON.
